C. R. MEYER.
CURTAIN BRACKET.
APPLICATION FILED NOV. 23, 1914.

1,163,840.

Patented Dec. 14, 1915.

UNITED STATES PATENT OFFICE.

CHARLES R. MEYER, OF DAYTON, OHIO.

CURTAIN-BRACKET.

1,163,840.

Specification of Letters Patent. Patented Dec. 14, 1915.

Application filed November 23, 1914. Serial No. 873,575.

To all whom it may concern:

Be it known that I, CHARLES R. MEYER, citizen of the United States, residing at Dayton, in the county of Montgomery and State of Ohio, have invented certain new and useful Improvements in Curtain-Brackets, of which the following is a specification.

My invention relates to curtain brackets and particularly to brackets of the adjustable type movable laterally to accommodate blinds and other hangings of different width.

The object of the invention is to simplify the structure as well as the means and mode of operation of such devices whereby they will not only be cheapened in construction but will be more efficient in use, easily adjustable, capable of being rigidly engaged in adjusted position, and unlikely to get out of repair.

With the above primary and other incidental objects in view, as will more fully appear in the specification, the invention consists of the features of construction, the parts and combinations thereof, and the mode of operation, or their equivalents, as herein-after described and set forth in the claims.

Referring to the drawings, Figure 1 is a perspective view of the adjustable curtain and blind bracket forming the subject matter hereof. Fig. 2 is a side elevation of the construction shown in Fig. 1, the shape of the supporting arm being slightly changed. Fig. 3 is a detail view of the engaging portion of the adjustable arm removed from the support or frame. Fig. 4 is a perspective view of a modification of the device embodying a locking means for positively engaging the adjustable arm with the support in its adjusted position. Fig. 5 is a side elevation of the assembled device showing a further modification of the locking means. Fig. 6 is a detail perspective view of the locking pawl employed in the construction shown in Fig. 5. Fig. 7 is a side elevation of a separable supporting arm, the sections of which are adapted to be interengaged one with the other in alternative relation. Figs. 8 and 9 are detail views of the interengaging parts by which the respective sections of the supporting arms shown in Fig. 7 are engaged one with the other. Fig. 10 is an end view of the supporting arm. Fig. 11 is a detail view of a modification of the frame.

Like parts are indicated by similar characters of reference throughout the several views.

The curtain and blind bracket forming the subject matter hereof is designed to obviate the necessity for relocation of the supporting brackets for blinds or other draperies of different width. The readjustment of the blind brackets or supports, particularly in rented houses where each tenant is provided with blinds of different width, causes the woodwork to become badly marred. By the use of the present device the brackets at the opposite sides of the window may be adjusted to and from each other throughout an extended range of movement sufficient to accommodate blinds of various width without changing the connection of the device with the window frame.

The blind bracket or support herein described comprises a frame member or support 1 adapted to be secured to the window frame, wall, or other structure, and an adjustable supporting arm 2 capable of lateral movement upon the base or frame 1 to various positions thereon and in addition to its lateral movement is capable of a limited vertical movement by which the supporting arm is securely engaged with the frame or support in its adjusted position. The frame or support 1 comprises a plate having in its upper edge a series of spaced notches or open slots 3 and adjacent to its opposite edge a series of holes or slots 4 closed at both ends. The plate is flanged or flared outward adjacent to its lower edge. The shape of the plate is such that the holes or slots 4 are located in the flanged or flaring portion of the plate. In the drawing the plate has been shown provided with an arcuate flange. It is obvious that the perforated lower portion of the plate may be bent outward in angular relation with the upper portion of the plate as in Fig. 11. At the opposite ends the plate is provided with extensions 5 which are turned rearward for a limited distance and then outward in parallel relation with the plate to form attachment ears by which the frame or support is secured to the window structure. If so desired, the lower flange or arcuate edge of the plate may be notched similar to the upper edge. In other words the slots 4 may be formed with open ends similar to the slots or notches 3, the sole object in forming the slots 4 with closed ends is to provide a continuous lower edge for the plate to assist in guiding the sup-

porting arm in its lateral movement. If the holes or slots 4 were open at their ends there might be a tendency for the supporting arm to engage in such notches during 5 its sliding movement and thereby interfere with the quick adjustment of the device. As shown in Fig. 1, the edge of the frame forms a continuous bearing upon which the arm slides. It is obvious that in the 10 event the slots 4 in the lower or flanged edge of the support are open at their ends, as before mentioned, the extension 8 of the slot 6-7 may be omitted as the object of the extension 8 is to receive the closed end 15 of the slot 4 when the supporting arm is depressed.

The supporting arm 2 comprises a flat plate having therein a vertical slot 6 terminating at its lower end in an arcuate portion 7 which communicates with a vertical extension 8 of the slot thereby forming intermediate the extension 8 and the main portion 6 of the slot a tongue 9. The frame or support 1 is introduced through the slot 20 6-7-8 by first introducing the ear 5 and turning the frame or support to enable the supporting arm to pass the angles of the extension of the plate until the arm passes into the main portion of the frame, 25 as shown in Fig. 2. When in this position the supporting arm 2 may be slidingly adjusted to and fro upon the frame or support 1.

When the supporting arm has been moved 30 to the desired position it is pressed downward through a limited vertical movement, as indicated by dotted lines in Fig. 2. This movement causes the tongue 9 to be projected through one of the slots or holes 4 in the flanged portion of the plate and at the same time causes the portion of the plate immediately above the main slot 6 to extend within the corresponding notch or slot 3 in the upper edge of the plate. The engagement of the tongue 9 in the slot or 35 hole at the bottom of the plate and the engagement of the upper portion of the arm in the slot 3 secures the supporting arm against further lateral movement and securely holds it against any tipping or tilting 40 movement in relation with the supporting frame 1.

To cause a more rigid engagement of the supporting arm with the frame, the tongue 45 5 may be bent slightly out of alignment with the plane of the supporting arm, as shown in Fig. 10. By so doing the tongue 9 is placed under tension when forced downward into the opening or slot 4 and thereby 60 provides a frictional engagement with the side of the slot tending to resist displacement of the supporting arm.

The particular shape of the extension of 65 1 the arm is shown provided with two tri-

angular notches 10 adapted to receive the supporting rod for a drapery or curtain. In Fig. 2 the arm is shown with a semicircular recess of comparatively large size to accommodate a curtain pole.

There is provided in the supporting arm 2 an opening 12 within which the trunnion of a roller blind 13 may be engaged. The opening 12 for the reception of the blind roller trunnion comprises preferably a circular 75 central portion having oppositely disposed notches or slots. The blind rollers commonly in use are provided with a round or cylindrical trunnion at one end and with a flat trunnion at the opposite end. The hole 80 or socket 12, as shown in the drawing, is adapted to accommodate either the round or flat trunnion. Thus the supporting arms are either right or left handed and may be used interchangeably. The usual boss or 85 bearing 14 is provided around the trunnion socket.

If so desired, various means may be employed for positively locking the supporting arm in its depressed position. Although 90 the frictional engagement of the unalined tongue 9, as previously described, will be found sufficient under ordinary circumstances, as a further precaution the tongue 9 may be provided with a hole 15 through 95 which a retaining pin or cotter may be introduced after the parts have been adjusted. Such pin or cotter will prevent the withdrawal of the tongue 9 from the hole or slot 4.

In Fig. 4 there is shown other means for locking the supporting arm in its depressed or adjusted position comprising a spring tongue or depressible bar 16 formed by slotting the main or central portion of the 105 supporting frame 1. The main slot 6 of the supporting arm 2 is provided with a lateral notch or recess 17 so located that the spring tongue or depressible bar 16 will engage therein when the supporting arm has 110 been depressed. The spring tongue will thus hold the supporting arm against withdrawal until the tongue has been pressed from the notch or recess 17. In Fig. 5 there is shown an additional oscillatory locking pawl 115 or detent 18 comprising a bit of metal, as shown in the drawing, inserted through a triangular opening 19 in the supporting arm adjacent to the slotted extension 8 and bent upon itself to parallelism about the side of 120 the opening. The shape and proportion of the detent is such that when resting upon the bottom of the opening 19 the preponderance of the weight of the detent on the side adjacent to the frame will cause it to 125 be oscillated beneath the flanged edge of the frame or support 1 thereby locking the supporting arm against withdrawal. The detent 18 is preferably provided with the projecting arm 20 by which the device may be con- 130

veniently withdrawn from locking position. The doubling of the material forming the detent around the sides of the opening 19 is merely a manufacturing expedient intended to cheapen the production. It is obvious that a detent pivoted to the supporting arm in the usual manner adjacent to the lower edge of the frame or support 1 will accomplish the same purpose.

10 In Fig. 7 there is shown a modification embodying an independent reversible extension 23 upon the supporting arm which may be interengaged with the frame engaging portion of the arm in either one of its positions. This independent arm is provided with a large semicircular recess upon one edge to engage a curtain or drapery pole of large diameter and is provided with two triangular recesses or notches in the opposite edge to engage rods of small diameter. The main portion 22 of the supporting arm is provided with the slot 6—7—8 and the trunnion socket 14 as before described. To detachably engage the main portion 22 and the detachable extension 23 one with the other, one of said members is provided with T shaped tongues 24 and 25 projecting perpendicular to the plane thereof. In the drawing these tongues have been shown upon the detachable extension as in Fig. 9. They might be located on the main portion 22. The other member is provided with two openings 26 and 27. These openings comprise slots substantially equal in size with the tongues 24 and 25 and correspondingly positioned in relation one with the other. The slots, however, are arranged in angular relation with the normal position of the tongues upon the independent extension.

40 The slot or opening 26 is provided with a triangular notch or recess in one side thereof, the side of said notch corresponding with the normal position of the tongue 24. The other slot or opening 27 is intersected by an arcuate slot 28 concentric with one end of the slot 26. The terminal of the slot 28 corresponds with the normal position of the tongue 25 when the parts are interengaged one with the other.

50 To interengage the parts the tongues 24 and 25 are inserted through the corresponding openings 26 and 27 and the independent extension is pressed upward to bring the stem of the T shaped tongue 24 into the lateral recess or notch of the slot 26. The independent extension is then oscillated about the bearing of the stem of the tongue upon the end of the slot 26 causing the stem of the tongue 25 to travel through the arcuate slot 28 until it engages the end of said slot. The stem of the tongue 24 then rests upon the shoulder of the offset or notch of the slot 26 which forms a fulcrum for the independent extension 23, the oscillatory movement 65 of which is resisted by the engagement of

the stem of the tongue 25 with the end of the slot 28.

To provide an increased bearing for the supporting arm upon the frame, the material of the arm adjacent to the slot 6 is bent 70 in opposite directions, as shown in Fig. 10. The material intermediate the slot 6 and the edge of the arm is deflected beyond the plane of the plate in one direction and the material adjacent to the opposite side of the slot is 75 deflected in the other direction. This provides a bracing effect which tends to resist any lateral oscillation.

From the above description it will be apparent that there is thus provided a device 80 of the character described possessing the particular features of advantage before enumerated as desirable but which obviously is susceptible of modification in its form, proportion, detail construction or arrangement 85 of parts, without departing from the principle involved or sacrificing any of its advantages.

While in order to comply with the statute the invention has been described in language 90 more or less specific as to certain structural features, it is to be understood that the invention is not limited to any specific details, but that the means and construction herein described comprise but one mode of putting 95 the invention into effect, and the invention is therefore claimed broadly in any of its possible forms or modifications within the scope of the appended claims.

Having thus described my invention, I 100 claim:

1. An adjustable bracket comprising a flanged frame member having a series of recesses in different angular faces thereof, a supporting arm slidingly mounted on the 105 frame and capable of a transverse movement in addition to its sliding movement by which the arm may be simultaneously engaged in corresponding recesses in the different angular faces of the frame.

2. An adjustable bracket comprising a flanged frame member having recesses in the flange thereof, a supporting arm having an offset slot therein through which the frame projects, said arm being capable of both 115 longitudinal movement and transverse movement in relation with the frame, and means for interengaging the arm in the recess of the flange of the frame by its transverse movement.

3. An adjustable bracket comprising an offset frame member having a series of marginal recesses therein and a series of recesses in the opposite portion thereof, a supporting arm having therein a slot through which the frame projects, said supporting arm being slidingly adjustable upon the frame, and adapted to be engaged in any two corresponding recesses thereof by a transverse movement.

4. An adjustable bracket comprising an offset frame having a series of recesses in the margin and a second series in the offset portion thereof, a supporting arm having a slot therein through which the frame projects, said arm being slidingly adjustable upon the frame and adapted to be simultaneously engaged with corresponding recesses of both series. 50
5. An adjustable bracket comprising an offset frame member having a series of openings in the offset portion thereof, a supporting arm slidingly engaged with the frame and adapted to be engaged in any one of the 55 openings of the frame by a transverse movement of the arm in relation with the frame. 55
6. An adjustable bracket comprising a frame having two series of openings in positions of the frame angular in relation one 20 with the other and a supporting arm to be simultaneously interengaged in corresponding openings of the two series by a transverse movement in relation with the frame. 60
7. An adjustable bracket comprising an offset frame member, having openings in the offset portion thereof, a supporting arm having an offset slot through which the frame member extends, the lip formed by the 25 offset of the slot being adapted to be projected into one of the openings of the frame by a transverse movement of the arm in relation with the frame. 65
8. An adjustable bracket comprising a frame member having a series of openings therein, a supporting arm having therein a bight shaped slot through which the frame member extends, and a tongue member formed by the bight shaped slot adapted to 30 be engaged in one of the openings of the frame. 70
9. An adjustable bracket comprising a frame member, a supporting arm having a slot therein through which the frame projects, said arm being capable of both longitudinal and transverse movement in relation with the frame, and means for interengaging the arm and frame by its trans- 45 75 80

verse movement, and a detent adapted to prevent return transverse movement. 50

10. An adjustable bracket comprising a frame member, a supporting arm slidingly adjustable upon the frame member, means for interengaging the arm with the frame by a transverse movement of the arm in relation with the frame, and a detent on the frame member adapted to engage a recess in the arm to prevent return transverse movement. 55

11. A bracket including a supporting arm 60 separable into parts, two T-shaped tongues projecting from one of the members, openings in the other member one of which is arcuate and positioned substantially concentric with the other through which the 65 tongues may be introduced and recesses communicating with said openings into which the tongues are moved by an oscillatory movement of the arm. 70

12. An adjustable bracket comprising a frame member, a supporting arm slidingly adjustable upon the frame member, means for interengaging the arm with the frame by transverse movement of the arm in relation with the frame, and a longitudinally 75 disposed depressible bar on the frame member adapted to engage a recess in the arm when the arm is at the limit of its transverse movement to lock the arm in adjusted position. 80

13. A bracket including a supporting arm separable into two parts, one of said parts having therein spaced key hole slots arranged in reversed relation one with the other, and corresponding headed projections carried by 85 the other part adapted to be introduced into the openings of the first mentioned part and interengaged therewith by an oscillatory movement. 90

In testimony whereof I hereunto set my hand this 14th day of November, 1914.
